UNITED STATES PATENT OFFICE.

HENRY D. KADEL, OF BROOKLYN, NEW YORK.

DESIGN FOR AN ELECTRIC BULB.

Application filed October 3, 1927. Serial No. 23,603. Term of patent 3½ years.

To all whom it may concern:

Be it known that I, HENRY D. KADEL, citizen of the United States, and resident of Brooklyn, New York, in the county of Kings and State of New York, have invented a new, original, and ornamental Design for Electric Bulbs, of which the following is a specification, reference being had to the

accompanying drawing forming part thereof.

Figure 1 is a top view, Figure 2 is an elevation of an electric bulb, showing my new design.

I claim:

The ornamental design for an electric bulb, as shown.

HENRY D. KADEL.
